UNITED STATES PATENT OFFICE.

FREDERICK C. GRISWOLD, OF PORT JEFFERSON, NEW YORK, ASSIGNOR TO OLIVE A. GRISWOLD, OF PORT JEFFERSON, NEW YORK.

FILM-SPlicer.

Specification of Letters Patent. Patented Oct. 26, 1920.

1,356,761.

Application filed December 27, 1917. Serial No. 209,076.

To all whom it may concern:

Be it known that I, FREDERICK C. GRISWOLD, a citizen of the United States, and resident of Port Jefferson, in the county of 5 Suffolk and State of New York, have invented a new and useful Improvement in Film-Splicers, of which the following is a specification.

The object of my invention is to provide 10 certain improvements in film splicing machines whereby the film sections may be easily and rapidly prepared for splicing and spliced without shifting the film sections lengthwise, means being employed to so trim 15 the ends of the film sections as to leave overlapping matched portions.

A practical embodiment of my invention is represented in the accompanying drawings, in which—

20 Figure 1 is a plan view of the machine with one of the film clamps lowered and the other one raised; the presser bar also being raised,

25 Fig. 2 is a section taken in the plane of the line II—II of Fig. 1,

Fig. 3 is a section taken in the plane of the line III—III of Fig. 1, with the farther film clamp and the presser bar lowered,

30 Fig. 4 is a view in perspective with the parts in the positions shown in Fig. 1, after the projecting end of one of the film sections has been trimmed by the knife on the film clamp which is shown raised,

35 Fig. 5 is an enlarged longitudinal vertical section through the machine taken in the plane of the line V—V of Fig. 1, with both film clamps and the presser bar lowered for splicing the overlapping ends of the two film sections,

40 Fig. 6 is a transverse section taken in the plane of the line VI—VI of Fig. 5, with the upper jaw of the farther clamp member raised and the lower jaw lowered,

45 Fig. 7 shows the trimmed end of one film section in bottom plan with the cement applied thereto and the trimmed end of the adjacent film section in top plan with the emulsion removed therefrom, and

50 Fig. 8 is a top plan view of both film sections after the overlapping ends have been brought together.

The base of the machine is denoted by 1. Lugs 2, 3, 4 and 5 uprise from the base at the back thereof, which lugs form supports for a bar 6.

At about the center of the base a lug 7 uprises therefrom, in which lug is seated a transversely arranged double shear block 8 having a flat horizontal top face. Between the uprising lugs 3 and 4, I hinge a presser 60 bar 9 having a yielding flat face 10 arranged to be brought into engagement with the top face of the shear block 8 when the presser bar is swung forwardly and downwardly.

65 A latch bar 11 is hinged to the front of the base 1 in position to engage the free end of the presser bar 9 when the presser bar is lowered. The shape of the hook 12 of the latch is such as to exert a cam-like action 70 on the free end of the presser bar 9 to force it into snug engagement with the shear block 8. In the present instance, this latch bar 11 is mounted on a bar 13 supported in lugs 14, 15; and spacing collars 13* are interposed between the latch bar and lugs. 75 This latch bar preferably has a slight yielding movement with the bar 13, to permit the latch bar to give sufficiently to adapt it to films of varying thicknesses.

80 An adjustable stop 16 at the back of the base is located in position to limit the upward and rearward movement of the presser bar.

85 Two film clamps are hinged on the bar 6, one on each side of the presser bar 9, between the lugs 2, 3, and 4, 5, respectively.

90 Adjustable stops 17, 18, are provided on the base 1 in position to support the clamps in their lowered position with the top faces 95 of their lower jaws 19 and 20 flush with the top face of the shear block 8.

95 Adjustable stops 21, 22, are located on the base 1 at the back thereof in position to engage the upper jaws 23, 24, respectively, of the film clamps when the clamps are swung upwardly and rearwardly to the limit of their movement in that direction.

100 The relative positions of the adjustable stops 21, 22, and the adjustable stop 16 are such that the meeting faces of the upper and lower jaws of the two film clamps will be flush with the yielding face 10 of the presser bar 9 when the clamps and presser bar are thrown back.

105 The lower jaws 19 and 20 of the film clamps are provided with suitable handles 25, 26, respectively, and the upper jaws 23, 24, of the clamps are provided with suitable handles 27, 28.

110

The upper jaws 23, 24, of the two clamps are held either opened or closed by springs 29, 30, which engage cam surfaces 31, 32, respectively, of said upper jaws. These 5 springs 29, 30, are secured to the bottom faces of the lower jaws 19 and 20.

The lower jaw 19 of one film clamp is provided with a shear blade 33 which is arranged to coact with the adjacent face of 10 the shear block 8 and the lower jaw 20 of the other film clamp is provided with a shear blade 34 arranged to coact with the opposite face of the shear block 8 for trimming off the rough projecting ends of adjacent film sections to be united as will herein-after more fully appear.

The lower jaws 19 and 20 of the film clamps are channeled along their upper faces to provide guides for the film sections 20 and the lower jaws are provided with up-rising registering pins 35, 36, for engaging the perforations along that side of the film sections.

The upper jaws 23, 24, of the clamps have 25 holes 37, 38, for receiving these registering pins when the jaws are closed.

In splicing film sections together, several 30 cycles of operations may be employed. For instance, presuming the film sections to be spliced with the emulsion side uppermost, the cycle of operations may be as follows: One film clamp, for instance the film clamp 19, 23, may be swung back out of the way as also the presser bar 9. The upper jaw 24 of 35 the other film clamp 20, 24, is raised and the film section is placed along the upper face of the lower jaw with the end to be trimmed projecting beyond the shear block 8 sufficiently to bring the cross line of one of 40 the picture divisions over the top face of the shear block. The film section will be held in this position by the registering pin 36. The upper jaw 24 is then closed. The other clamp 19, 23, is then swung downwardly thus 45 causing its cutter blade 33 to shear off the portion of the film which projects beyond the cutter block. The film clamp 20, 24, is then swung back out of the way and the upper jaw 23 of the clamp 19, 23, is then raised. 50 The other film section is then placed in the lower jaw 19 with its end to be trimmed projecting beyond the shear block 8 and with the cross line of one of the picture divisions located on the top face of the shear 55 block.

This film section will be held in place by the registering pin 35. The upper jaw 23 is then closed. The film clamp 20, 24, is then lowered, causing its cutter blade 34 to coact 60 with the shear block 8, to trim off the portion of the film projecting beyond the shear block. This will leave the ends of the two film sections overlapping on the top face of the shear block. The film clamp 20, 24, may 65 then be swung back bringing its projecting

end onto the yielding face 10 of the presser bar 9.

In the condition being described, with the film sections placed in the machine with the emulsion on top, the emulsion on the projecting end of the film section held by the clamp 19, 23, which is resting upon the shear block 8, may be removed in any desired manner, as, for instance, by the treatment with a chemical which will remove the 70 emulsion or by a scraper or by an abrasive implement, such as a block of dampened felt. The cement may then be applied either to the exposed surface of the raised film section or to the exposed surface of the 75 lowered film section. The film clamp 20, 24, may then be lowered, bringing the exposed portion of this film section onto the exposed portion of the film section held by the lowered clamp 19, 23.

The presser bar 9 may then be swung downwardly and from its free end engaged by the cam latch 11 to force the yielding face 10 of the presser bar snugly into engagement with the overlapped ends of the 90 two film sections. The parts may be maintained in this position sufficiently long to permit the ends to be firmly united when the presser bar and the upper jaws of the two film clamps may be thrown back to 95 permit the removal of the united film sections.

The function of the yielding face 10 of the presser bar is to insure an even pressure along the overlapping ends of the film sections even should they vary in thickness.

While I have described the operation of the machine in connection with uniting the severed ends of two film sections, it is obvious that it might as well be employed for 105 cutting out a portion of a film and joining the remaining portions or it might be used for joining the ends of two different films.

It will be seen from the above description that the film sections are controlled absolutely from the beginning of the operations without any tendency of the film sections to shift.

It will also be seen that the matching up of the film sections can be done very rapidly 115 by bringing the cross lines of their picture divisions over the shear block.

It will also be seen that after the two ends have been trimmed, they are already overlapped, thus obviating the necessity of shifting film sections endwise before they are united.

It will also be seen that one or both of the film carrying clamps may be swung into and out of engagement with the shear block 125 as desired, thus permitting ready preparation of the film sections for splicing without the necessity of rolling back one or both ends for treatment.

It will also be seen that after the ends are 130

trimmed, the projecting portions of both film sections are supported by a flat surface whether the clamps be raised or lowered.

By making the stops for limiting the forward and rearward movements of the clamps adjustable, I am enabled to bring the film carrying surfaces of the clamps into absolute alinement with the top face of the shear block when the clamps are lowered or 10 with the yielding face of the presser bar when the clamps are raised.

It will be noted that the shear blades are carried by the film clamps rather than by a separate operative device, the shear block 15 serving both to coat with the shear blades and also with the presser bar in the cycle of operations.

What I claim is:—

1. In a film splicer, means for separately 20 clamping two film sections, registered with respect to each other, means for so trimming the ends of said sections as to leave overlapping portions without endwise movement of the sections, and means for pressing the 25 overlapping portions of the film sections together.

2. In a film splicer, a double shear block and a pair of film clamps having cutting edges arranged to coat with the shear block 30 for trimming the ends of the film sections.

3. In a film splicer, a double shear block and a pair of film clamps having cutting edges arranged to alternately coat with the shear block for so trimming the ends of two film 35 sections as to leave overlapping portions in the plane of the shear block.

4. In a film splicer, a double shear block, a pair of film clamps having cutting edges arranged to alternately coat with the shear 40 block for so trimming the ends of two film sections as to leave overlapping portions in the plane of the shear block, and a presser bar arranged to press the overlapping ends together on the shear block.

45 5. In a film splicer, a double shear block, a film clamp on each side of the shear block, each clamp having a cutting edge for trimming the end of the film section held by the other film clamp, thereby leaving overlapping ends in the plane of the shear block.

6. In a film splicer, a double shear block, a film clamp on each side of the shear block, each clamp having a cutting edge for trimming the end of the film section held by the other film clamp, thereby leaving overlapping ends in the plane of the shear block, and a presser bar for pressing the overlapping ends together on the shear block. 55

7. In a film splicer, a double shear block, swinging film clamps on opposite sides of the block having cutting edges for trimming the ends of the film sections held by the clamps, and a swinging presser bar for pressing the overlapping ends together on the shear block. 60

8. In a film splicer, a double shear block, swinging film clamps on opposite sides of the block having cutting edges for trimming the ends of the film sections held by the clamps, a swinging presser bar for pressing the overlapping ends together on the shear block, and stops for limiting the swinging 70 movements of the clamps and presser bar.

9. In a film splicer, a double shear block having a flat top, a pair of film clamps located on opposite sides of the block, each comprising upper and lower swinging jaws, means for registering each film section on the top of the shear block and maintaining it in such register and means carried by each 80 clamp for trimming the end of the film section carried by the other clamp, thereby leaving overlapping portions. 75

10. In a film splicer, a double shear block having a flat top, a pair of film clamps located on opposite sides of the block, each comprising upper and lower swinging jaws, means for registering each film section on the top of the shear block and maintaining it in such register, means carried by each 85 clamp for trimming the end of the film section carried by the other clamp, thereby leaving overlapping portions, and means for uniting said overlapping portions on the shear block. 90

In testimony, that I claim the foregoing as my invention, I have signed my name this 22nd day of December 1917. 95

FREDERICK C. GRISWOLD.
